UNITED STATES PATENT OFFICE

FRANK L. GRAY, OF SHELBURNE FALLS, MASSACHUSETTS

HAY-LOADING WAGON

Application filed May 7, 1928. Serial No. 275,875.

This invention relates to a combined hay loader and wagon, and has for one of its objects to provide a novel, simple and highly efficient apparatus of this character wherein 5 the loader shall be arranged in the rear of the wagon and wherein the drive wheels of the loader shall constitute the rear wheels of the wagon and the front wheels of the wagon shall constitute the front wheels 10 of the loader, whereby to permit the loader to be so connected to the wagon as to insure its having the same position with respect to the wagon when the apparatus is turning a corner as it occupies when the apparatus is moving in a straight path and thus 15 permit the rack of the wagon to be provided with sides as high or higher than the loader and permit the loader to be utilized as a support for the rear end of the wagon.

20 The invention has for a further object to provide an apparatus of the character stated which shall embody novel, simple and efficient means for securing the wagon and loader together.

25 With the foregoing and other objects in view, the nature which will appear as the description proceeds, the invention consists in the construction, combination and arrangement of parts hereinafter fully described and 30 claimed, and illustrated in the accompanying drawings wherein:—

Figure 1 is a view in side elevation of the wagon,

35 Figure 2 is a view in side elevation of the loader,

Figure 3 is a sectional view taken on a vertical plane extending centrally and longitudinally through the wagon and loader in assembled and connected relation,

40 Figure 4 is a side elevation of the wagon and loader in assembled and connected relation,

Figure 5 is a sectional view taken on the planes indicated by the line 5—5 of Figure 4,

45 Figure 6 is a sectional view taken on the planes indicated by the line 6—6 of Figure 3,

Figure 7 is a sectional view taken on the horizontal plane indicated by the line 7—7 of Figure 6.

50 Figure 8 is a sectional view taken on the

vertical plane indicated by the line 8—8 of Figure 7,

Figure 9 is a sectional view taken on the horizontal plane indicated by the line 9—9 of Figure 4,

55

Figure 10 is a perspective view of the base frame of the loader,

Figure 11 is a perspective view of the rear end of the bed frame of the wagon,

Figure 12 is a perspective view of one of the trusses of the means for securing the wagon and loader together,

Figure 13 is a perspective view illustrating the manner in which the bed pieces or beams of the wagon are secured to the frame of the 60 loader, and

Figure 14 is a sectional view taken on the vertical plane indicated by the line 14—14 of Figure 13.

The wagon comprises ground wheels 1, an axle 2, and a bolster 3 which is secured to the axle by a pivot 4 similar in construction to a fifth wheel. A cross beam or stick 5 is secured upon the bolster 3 and extends beyond the 70 wheels 1. Longitudinal beams 6 and 7, which are arranged beneath the cross beams 5, are secured to the cross beam in a suitable manner. The beams 6 are arranged inwardly of and extend rearwardly beyond the beams 7, and the beams 6 and 7 are connected at their front ends by a cross beam 8. A rear bolster 9 is secured to and between the beams 6, and is located near the rear ends of the beams.

The bolster 9 extends for a considerable distance below the beams 6, and is provided at its lower edge and centrally between its ends with a notch or recess 10, the purpose of which will presently appear. The bolster 9 is of sectional formation, the sections 9^a and 9^b thereof are secured together by a strap 11, and the section 9^a thereof is secured directly to the beams 6. A reach bar 12 which is located at the longitudinal center of the wagon, is secured to and between the bolsters 3 and 9 by strap bolts 13 and 14. Slatted sides 15 are secured to the beams 7, a slatted front end 16 is secured to the cross beam 8, a slatted rear end 17 is secured to and between the sides and has an upwardly and forwardly inclined upper portion; and a slatted bottom 18 is secured

upon the beams 6 and 7. Braces 18^a extend from the bottom 18 to the lower edge of the bolster 3, and a draft bar or tongue 19 is connected to the axle 2.

5 The beams, bolsters and reach bar constitute the bed frame of the wagon. The slatted sides and ends constitute the hay receiving rack of the wagon. The wheels are arranged slightly in advance of the transverse center 10 of the wagon. The tongue or draft pole provides means by which the wagon may be connected to a tractor.

The loader which is of well known construction, comprises drive wheels 20, an axle 21 to which the wheels are fixed, and a base frame 22 connected to the axle by bearings 23. A drum 24 is fixed to the axle 21 and is provided with teeth 25 which, when the apparatus is in operation, picks up the hay and 20 carries it to a conveyor belt 26 which inclines upwardly and forwardly and discharges the hay into the rack of the wagon. The conveyor belt 26 comprises sprocket chains 27 and flights 28. The sprocket chains 25 pass about sprocket wheels 29 fixed to the axle 21 and sprocket wheels 30 carried by a shaft 31 journaled in the upper end of a frame 32. This frame inclines upwardly and forwardly from the frame 22, and is secured to the frame 22 through the medium of rear 30 supporting members 33 and 33^a of inverted U-form and front supporting members 34 of V-form.

The frame 22 is provided with a draft bar 35 or tongue 35 which has its front end or nose positioned in the notch 10 of the rear bolster 9 and is secured snugly against the bolster by truss bars 36 and 37 of V-form. The truss bars 36 and 37 are arranged at opposite sides 40 of the rear bolster 9, embrace the tongue 35 and are secured at their ends to the beams 6. Brackets 38 are secured to the upper ends of the sides of the supporting member 33, as at 39, and are provided with shoulders 40 which 45 rest upon the top of the support. The rear ends of the beams 6 are secured to the brackets 38, as at 41.

A plate 42 is secured to one of the strap bolts 14 and contacts with the rear side of the 50 supporting member 34.

The truss bars 36 and 37, the brackets 38 and the plate 42 constitute a coupling through the medium of which the wagon and loader are connected, and in view thereof the loader 55 will have the same position with respect to the wagon when the apparatus is turning a corner as it occupies when the apparatus is moving in a straight path.

From the foregoing description, taken in 60 connection with the accompanying drawings, it will be apparent that the wagon wheels 1 constitute the front wheels of the loader and the loader wheels 20 constitute the rear wheels of the wagon, that the wagon and loader have fixed a position with respect to each

other, and that due to these features the sides and ends of the rack of the wagon may be made as high or higher than the loader. The height of the sides and ends of the rack prevents the hay from falling off of the rack. The height of the sides and of the rack and the fixed position of the loader with respect to the wagon insure the discharge of the hay from the loader directly into the rack whether the apparatus is turning a corner or traveling in a straight path, and due thereto it is not necessary to employ a man on the rack. As it is unnecessary to employ a man on the rack the apparatus can be run at a speed only limited by the nature of the ground and the power of the tractor pulling the apparatus. Furthermore, there will be no scattering of the hay as none can fall off the rack and none will be shot off the rack to one side while the apparatus is turning a corner. The apparatus will gather and load the hay into the rack twice as fast as it is possible to do so by three men employing a tractor, wagon and separate loader. The end of the rack will keep the hay away from the loader belt 26.

99 While I have described the principle of operation of the invention together with the structure which I now consider to be the best embodiment thereof, I desire to have it understood that the device shown is merely 95 illustrative, and that such changes may be made when desired as are within the scope of the invention as claimed.

What I claim is:

An apparatus of the character set forth, 100 comprising a wagon, steering wheels supporting the same, beams mounted upon said wagon, a rack mounted upon the beams, a bolster secured to the beams adjacent the rear ends of the latter, a load having a supporting member, means securing the supporting member to the beams for anchoring said loader against lateral swing with respect to said wagon, said means comprising brackets provided with inwardly extending shoulders 105 resting upon said supporting member, the bracket being secured to said securing member and also to said beams, and wheels supporting said loader.

110 In testimony whereof I affix my signature. 115
FRANK L. GRAY.
